(57) **CLAIM**

The ornamental design for an LED flashlight, as shown and described.

DESCRIPTION

FIG. 1 is a perspective view of the LED flashlight showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial enlarged view of portion 9 in FIG. 1;

FIG. 10 is a perspective view thereof when the stand of the LED flashlight is restored;

FIG. 11 is a perspective view thereof when the stand of the LED flashlight is in an open configuration;

FIG. 12 is a perspective view thereof when the stand of the LED flashlight is in a curved configuration; and,

FIG. 13 is a perspective view thereof when the stand of the LED flashlight is in another curved configuration.

The broken lines in the drawings depict portions of the LED flashlight that form no part of the claimed design. The additional broken lines shown in FIG. 13 depict environmental subject matter that forms no part of the claimed design. The dot-dash lines surrounding the detail views are for annotative purposes only and form no part thereof.

1 Claim, 13 Drawing Sheets
